FEED CLEANER FOR GRAIN GRADER SAMPLE DIVIDERS

Homer L. Brundage, Toledo, Ohio

Application August 12, 1940, Serial No. 352,245

3 Claims. (Cl. 209—223)

This invention relates to culling out magnetizable matter from grain tester samples.

This invention has utility when incorporated in a cone spill receiving electromagnetic device feed to the hopper of a sample divider.

Referring to the drawing:

Fig. 1 is a side elevation, with parts broken away, of an embodiment of the invention as adapted to a sample divider for grain graders;

Fig. 2 is a section on the line II—II, Fig. 1, showing the view looking down on the magnetizable cone or metal accumulator part; and

Fig. 3 is a section on the line III—III, Fig. 2, showing the relation of the supply feed section to this magnetizable cone and its chute therefrom to the hopper.

In practice, grain standards have to do with gathering samples of cereals, legumes, seeds, in say 5 or 6 pound bags or thereabouts. Such samples for the grain tester are poured into hopper 1 of grain divider device 2 in the usual course of working supply material 3 from bag or packages 4. These samples, whether beans, seeds of the smaller type, or even wheat, oats, barley, or corn, in the harvesting or processes as variously handled, especially by machinery, may at times accumulate foreign material which it is desirable to cull therefrom. A character of this foreign material which may be contributed by the containers or parts of the machines through which passing is of the magnetizable class and may be small nails, nuts, bolts, etc.

In the practice hereunder, electric supply 5 may have fixture 6 with conductor line 7 therefrom to switch 8 with conductor lines 9, 10, therefrom. In the event this supply current be direct current these lines 9, 10, may be directly connected to terminals 11, 12, at insulation bracket 13 on upright bracket 14 from chute 15. This chute 15 has additional brackets 16 therefrom, which with the bracket 14 mount supply or feed way tapered hopper or cone 17 to receive the spill of granular material 3. In the event the electric current or power supply at fixture 5 be alternating, the lines 9, 10, may connect to lines 18, 19, of rectifier 20, say of the radio type, at which switch 21 may function through the action say of a transformer and six ohm resistor so that the 110 volt supply current may be brought down to 6 to 8 volts as taken from terminals 22, 23, by conduit 24 to the terminals 11, 12.

From the terminals 11, 12, extends conduit 25 to coil 26 in cup 27 carried by radiating arms 28 centrally of the chute or duct portion 15. This

cup 25 as carrying the coil 26 has top closure 29 upon which rests tapered insulation or wood ring 30. In the ascent of this ring 30, it is flush with core 31 of this electromagnet coil 26. This core 31 has tapered apex 32 located centrally of spill opening 33 from the supply way 17. Accordingly, with this electromagnet energized, whether by a 110 volt direct current or by the lower voltage rectified current, spill of granular material into the way 17 has such in its downward travel directed against this apex 32 as magnetized, whereupon this magnetic material adheres thereto as the regular seed or grain is free to flow in this angle of drop, say of approximately 30°. Thus 10 the supply of the granular material freely flows from this supply way 17 past the magnetic collector apex 32 as to the granular material non-magnetic, and from thence into the chute portion 15 to be delivered to the divider hopper 1. As the 15 respective samples from the containers 4 are spilled into the way 17, it is but in order for the operator as having the switch on, before the pour starts, to check the condition of this apex 32 and, as there is culled out iron or magnetic material, for the operator to clear such cone apex of the magnetic material before there is the subsequent sample supplied.

What is claimed and it is desired to secure by 20 United States Letters Patent is:

1. For assembly with a sample divider of the grain grader type having an upwardly open circular hopper, a chute for delivery to and mounted on said hopper, a circular tapered portion centrally in the chute having a central magnetic and a surrounding non-magnetic face section, and directing means providing a spill of granular material to lodge directly on said central face to spill therefrom over the non-magnetic face and be then directed by said chute into the hopper with the magnetic face section effective to retain magnetizable material thereon as the non-magnetic granular material passes therefrom.

2. For assembly with a sample divider of the grain grader type having an upwardly open circular hopper, a chute for delivery to and mounted on said hopper, a cone centrally of the chute, said cone having a magnetic apex section flush with a non-magnetic frustum section, and directing means providing a spill of granular material to lodge directly on said magnetic apex section to spill therefrom over the non-magnetic frustum section and be then directed by said chute into the hopper with the magnetic apex section effective to retain magnetizable material thereon as

the non-magnetic granular material is free to pass over the said frustum section.

3. For assembly with a sample divider of the grain grader type having an upwardly open circular hopper, a chute for delivery to and mounted on said hopper, a ring shaped non-magnetic section tapering inwardly and upwardly, and an electromagnet having an apex filler for the ring as a continuation thereof in forming a cone, and

5 directing means providing a spill of granular material to lodge directly on said magnetic apex for the non-magnetic material to be directed therefrom by said chute into the hopper with the magnetic apex effective to retain magnetizable material thereon as the non-magnetic granular material passes therefrom.
